UNITED STATES PATENT OFFICE.

GEORGE H. BOCKIUS, OF CANTON, OHIO, ASSIGNOR TO DIEBOLD SAFE & LOCK COMPANY, OF CANTON, OHIO, A CORPORATION OF OHIO.

AUXILIARY LOCK.

Application filed September 28, 1926. Serial No. 138,184.

The invention relates to auxiliary locks for bolt work, and more particularly to an auxiliary locking device for the bolt work of the ordinary locking mechanism for the doors of 5 safes and vaults.

Safe and vault doors have been provided with auxiliary locking devices for automatic operation to lock the bolt work of the doors when the same are tampered with either by 10 oxy-acetylene or other torch flames, or explosives, for preventing operation of the bolt work and thereby preventing opening of the doors.

Auxiliary locking devices of this character 15 which have heretofore been used, include a relatively large number of working parts, each different from the others, and have consequently been relatively difficult and relatively expensive to manufacture; and, in 20 use, have been relatively difficult of adjustment for certainty of operation at all times.

The objects of the present improvements are generally to overcome the foregoing structural, manufacturing, economic, and operating 25 difficulties, and are specifically:—

First, to provide an auxiliary lock for the bolt work of vault doors and the like, having a minimum number of working parts, and adapted for easy and economical manufac- 30 ture; and

Second, to provide an auxiliary lock for the bolt work of a vault door and the like made of a minimum number of parts constructed and arranged for simplicity and certainty of 35 operation.

These and ancillary objects are attained in the present improvements by a construction and arrangement which may be stated in general terms as including a heavy weight 40 suspended in an upright channel or guideway provided therefor in the vault door, by means of a fragile supporting member arranged to separate upon an application of heat or explosion, such as a chain including 45 one or more links formed of a metal which fuses at a low temperature, and which may be shattered by an explosion, there being a preferably cylindric pin mounted upon the weight and normally extending therefrom in 50 alinement with parts of the bolt work for permitting operation thereof, but adapted for movement to prevent operation of the bolt work when one or more of the fusible and fragile links are fused or shattered, and the 55 weight drops.

Preferred embodiments of the invention are illustrated in the accompanying drawings, forming part hereof, in which—

Figure 1 is a rear elevation of a rectangular vault door showing the application of the 60 invention to the usual bolt work the auxiliary lock being in normal inoperative position;

Fig. 2, a fragmentary enlargement of the lower right hand corner of Fig. 1, illustrating in detail the improved auxiliary lock in 65 operative position;

Fig. 3, a fragmentary and enlarged perspective view illustrating the internal as well as the external construction and arrangement of the door and auxiliary lock of Fig. 1; 70

Fig. 4, a fragmentary perspective view of a circular vault door illustrating a modified form of the invention adapted for providing an auxiliary locking mechanism for the bolt work of a circular door. 75

Similar numerals refer to similar parts throughout the drawings.

A rectangular door for a safe or vault is indicated generally at 10, and may include a plurality of plates 11, 12, 13, and 14, preferably made of different grades of steel, certain of the plates as 13 being of multiple ply material and drill resisting, and certain of the plates as 12 being torch resisting. 80

The usual bolt bars 15 and 16 are arranged 85 in parallel relation on the face of the door, and the usual locking bolts 17 are slidably located through said bars and arranged to be moved in unison by means of the bolt carrying bars 18, one of which is provided for 90 each side of the door, and all of the locking bolts on each side of the door being connected to the bolt carrying bar.

A pair of alined rack bars 19 is connected to the upper and lower bolt carrying bars, 95 each of said rack bars being engaged upon opposite sides by the pinions 20 and near its inner end by pinion 21. A pair of short rack bars 22 is connected to each of the side bolt carrying bars and engages the adjacent pinion 20. 100

The operating bar 23 is provided with rack portions engaging the pinions 21 and with a rack portion 24 engaging the pinion 25 upon the operating spindle 26. All of the above 105 construction is usual in safe and vault door work, and may be varied to some extent, and does not form a part of the present invention.

An upright channel or guideway 27 having an enlarged lower weight chamber 28 is pro- 110

vided in the door preferably at the rear of plate 11, and the weight 29 is suspended therein upon a fragile supporting member arranged to separate upon the application of 5 heat or explosion, such as a chain composed of alternate links 30 and 31, supported at its upper end as by a screw plug 32, the links 31 being formed of a metal which fuses at a low 10 temperature, and which may be shattered by an explosion.

The preferably cylindric pin 33 is mounted in the weight 29, and extends laterally therefrom through a vertically elongated aperture 34 in the rear door plates.

15 The pin 33 is normally in alinement with a horizontally extending notch 35 preferably in the right hand lower short rack bar 22 of the bolt work.

As illustrated in Figs. 1 and 3, the bolt 20 work is in extended and locking position, and the slot 35 in the lower right hand rack bar 22 being sufficiently large to pass over the pin 33 and normally alined therewith, the bolt work may be operated at all times when 25 the pin 33 is alined with the slot 35, rotation of the spindle 26 operating all of the rack bars and pinions, to withdraw or extend all of the locking bolts 17 in the usual manner.

The bolt work being in locked or extended 30 position, when an oxy-acetylene or other torch or an explosive is used in an attempt to open the door 10 by an unauthorized person, one or more of the alternate links 31 will be melted or shattered allowing the weight 29 35 to drop to the bottom of its chamber 28.

When the weight drops, as illustrated in Fig. 2, the pin 33 drops with it out of alinement with the notch 35 in the lower right hand rack bar 22, back of and preferably in 40 abutment with the lower left hand corner 36 thereof, thereby dogging off and stopping the withdrawal of the lower right hand rack bar 22 and thereby preventing operation of the entire bolt work.

45 The modified form of the invention as applied to a circular door indicated generally at 10' illustrated in Fig. 4, includes a plurality of plates 11', 12', 13', 14', and 14", preferably made of different grades of steel, certain of the plates as 13' being of multiple ply material and drill resisting, and certain of the plates as 12' being torch resisting.

55 Circular bolt bars 15' and 16' are arranged in concentric relation on the face of the door, and the usual radial locking bolts 17' are slidably located through said bars and arranged to be moved in unison by usual circular door bolt mechanism, not shown.

A bell crank 37 is pivoted as by cap screw 60 37' upon the inner surface of the door, and one normally vertical arm 38 of the bell crank extends upwardly so that its upper end 39 may normally freely rotate just below the lower surface of a laterally extending pin 33' mounted on a weight 29' and laterally extend-

ing outward therefrom through a vertically elongated aperture 34' in the rear door plates, the weight being suspended in the lower weight chamber 28' of a vertically extending channel or guideway 27' in the door, as by 70 means of a chain including alternate links 30' and 31', the links 31' being formed of a metal which fuses at a low temperature and which may be shattered by an explosion.

The other bell crank arm 40 angular to 75 the vertically extending arm 38 is provided with an elongated slot 41 in which slot extends a screw plug 42 mounted in the lower end of one of the radial bolts 17'.

As illustrated in Fig. 4, the bolt work is 80 in extended position and the auxiliary locking mechanism is inoperative, withdrawing of the bolts merely causing the upper end 39 of the bell crank arm 38 to pass beneath the lower surface of the pin 33'.

When an oxy-acetylene or other torch or an explosive is used in an attempt to open the circular door 10' by an unauthorized person one or more of the alternate links 31' will be melted or shattered, allowing the weight 29' to drop to the end of its chamber 28'. When the weight drops, the pin 33' drops with it alongside of the outer edge face 43 of the bell crank arm 38 below the upper end 39 thereof, thereby dogging off 85 and preventing movement of the bell crank arm and thereby preventing movement of the bolts.

The foregoing embodiments of the invention provide an auxiliary locking device, 100 either for a rectangular or circular door, which includes a relatively few number of working parts, and easy and economical to manufacture, and adapted for simplicity and certainty of operation when an oxy-acetylene or other torch or an explosive is used in an unauthorized attempt to open the door, for positively locking the bolt work against withdrawing and preventing opening 105 of the door.

In order to prevent an unauthorized person from drilling a hole through from the front of a vault door provided with the improved auxiliary lock for its bolt work, as herein set forth, it is preferred to place one 115 of the drill-proof plates 13 or 13' in front of the weight, as illustrated in Figs. 3 and 4.

If an unauthorized person could drill a hole through the door from the front, it would be possible to insert a wire, chisel, 120 or other tool, and either prevent the falling of the weight, or lift the same after it has fallen.

By providing the drill-proof plates in 125 front of the weights, as aforesaid, such tampering with the auxiliary lock is prevented.

In order likewise to prevent an unauthorized person from burning a hole through the front of a vault door with the improved auxiliary lock for its bolt work, as herein 130

set forth, it is preferred to place a substantial thickness of torch resisting plate as 12' in front of the weight, as illustrated in Fig. 4.

5 I claim:

1. An auxiliary lock for the bolt work and the like of vault doors and the like, including a fusible chain suspended upon the door, a weight suspended by the chain, 10 a bolt work for the door, and a pin mounted upon the weight and normally extending laterally therefrom in alinement with parts of the bolt work for permitting normal operation thereof, the pin being movable to dog off and prevent operation of the bolt work when the chain is fused or shattered.
2. An auxiliary lock for the bolt work and the like of vault doors and the like, including a fusible chain suspended upon the door, a 20 weight suspended by the chain, a bolt work for the door having a notch in one of its parts, and a pin mounted upon the weight and normally extending laterally therefrom in alinement with the bolt work notch for permitting normal operation of the bolt work, the pin being movable out of alinement with the bolt work notch to dog off and prevent operation of the bolt work when the chain is fused or shattered.

3. An auxiliary lock for the bolt work and the like of vault doors and the like, including a guideway in the door, a fusible chain suspended upon the door, a weight suspended from the chain in the guideway, a bolt work for the door, and a pin mounted upon the weight and normally extending laterally therefrom in alinement with parts of the bolt work for permitting normal operation of the bolt work, the pin being movable to 30 dog off and prevent operation of the bolt work when the chain is fused or shattered.

4. An auxiliary lock for the bolt work and the like of vault doors and the like, including a guideway in the door, a fusible chain suspended upon the door, a weight suspended from the chain in the guideway, a bolt work for the door having a notch in one of its parts, and a pin mounted upon the weight and normally extending laterally therefrom in alinement with the bolt work notch for 40 permitting normal operation thereof, the pin being movable out of alinement with the bolt work notch to dog off and prevent operation of the bolt work when the chain is fused or shattered.

5. In testimony that I claim the above, I have hereunto subscribed my name.

GEORGE H. BOCKIUS.
